UNITED STATES PATENT OFFICE.

WINNIE D. DEAL, OF SPENCER, NORTH CAROLINA.

PLAYING-CARDS.

1,275,869.

Specification of Letters Patent. Patented Aug. 13, 1918.

Application filed June 5, 1918. Serial No. 238,317.

To all whom it may concern:

Be it known that I, WINNIE D. DEAL, a citizen of the United States, residing at Spencer, in the county of Rowan and State 5 of North Carolina, have invented certain new and useful Improvements in Playing-Cards, of which the following is a specification, reference being had therein to the accompanying drawings.

10 This invention relates to playing-cards that are characterized by signatures and key-notes of the various major and minor scales.

15 It is an object of the invention to provide a deck of cards suitable for use at musical gatherings, club meetings, and other social occasions, in order that the players may become familiar with musical scale signatures, key-notes, and formulas.

20 The deck provided by the invention is made up of several suits of cards, of equal number, there being a major-flat, major-sharp, minor-flat, and minor-sharp suit.

25 The particular cards making up the deck employed as contemplated by the invention are exemplified by the accompanying drawings, forming part hereof, in which—

Figure 1 represents the scale-ladder card of the major-flat suit;

30 Fig. 2 represents one of the other cards of the major-flat suit;

Fig. 3 represents the major-flat-circle card;

35 Fig. 4 represents a card of the major-sharp suit;

Fig. 5 represents the scale-ladder card of the minor-flat suit;

Fig. 6 represents another card of the minor-flat suit;

40 Fig. 7 represents a card of the minor-sharp suit; and

Fig. 8 represents the minor-sharp-circle card.

45 The characters and other symbols on the faces of the cards of each suit are of a color different from those of the other suits, and capital letters are used on the cards of the two "major" suits and small letters on those of the two "minor" suits. The cards are 50 numbered consecutively from 1 to 10.

Card No. 1 of each suit is a scale-ladder card, it having on its face a representation of a ladder showing by the spacing of its rounds or steps the correct intervals of the

scales, the rounds or steps being numbered 55 consecutively from 1 to 8, as shown by Figs. 1 and 5.

Card No. 2 of each suit bears a letter of the scale of that suit, in the exemplification herein made this letter being "C" in the 60 case of the two "major" suits and "a" in the case of the two "minor" suits, Fig. 2 showing card No. 2 of the major-flat suit, Fig. 4 card No. 2 of the major-sharp suit, Fig. 6 card No. 2 of the minor-flat suit, and 65 Fig. 7 card No. 2 of the minor-sharp suit.

Each of the cards Nos. 3 to 9, inclusive, of each suit bears a letter representing the key-note of the scale to which that suit pertains. Each card represents a different scale, and 70 the letter thereon is the first of the scale—or key-note. Thus, in the major-flat suit, there are cards "F", "Bb", "Eb", "Ab", "Db", "Gb", and "Cb"; in the major-sharp suit, cards "G", "D", "A", "E", "B", "F#", and 75 "C#"; in the minor-flat suit, cards "d", "g", "c", "f", "b", "eb", and "ab"; and, in the minor-sharp suit, cards "e", "b", "f", "c#", "g#", "d#", and "a#". Each scale of each of the two "flat" series starts on the fourth 80 note of the preceding scale; that is, taking the major-flat suit as an example, card No. 2 is "C" and card No. 3 bears "F", the fourth note from "C". Each scale of the two "sharp" series starts on the fifth note 85 of the preceding scale; that is, taking the major-sharp suit as an example, card No. 2 is "C" and card No. 3 is "G", the fifth note from "C".

Each of the cards from 2 to 9, inclusive, 90 has thereon the key signature of the scale indicated thereon by letter; as in the major-flat suit; for example, card No. 2 has the treble clef with no flats, card No. 3 the treble clef with one flat, and so on to card No. 9 95 with the treble clef with seven flats.

Card No. 10 of each suit bears a circle, around which are arranged in progressive order the letters and key-signatures on the treble clef of the scales indicated by the 100 cards numbered 2 to 9, inclusive. In the case of the "flat" suits, the numeral "4" is between each pair of designations, indicating a four count between the notes designated. For example, the major-flat card No. 10 has 105 around the circle the following: "C 4 F 4 Bb 4 Eb 4 Ab 4 Db 4 Gb 4 Cb," and radially arranged from each letter the clef signature of

the note indicated by the letter. In the case of the "sharp" suits, the numeral "5" is between each pair of designations, indicating a five count between the notes designated.

- 5 Each of the cards of every suit has on its face at one or more places a word indicating whether it is of a "flat" or "sharp" suit, as the word "Flats" in the major-flat suit and "Sharps" in the minor-sharp suit; cards 10 Nos. 1 to 9, inclusive, of every suit have thereon the word "Major" or "Minor," as the case may be; and card No. 10 has within the circle words indicating the character of the card, as "Major sharp circle" and 15 "Minor flat circle."

The cards may be used in play in any manner the players may decide in order to stimulate their interest in and knowledge of major and minor scales.

- 20 As an example of a desirable manner of use, the following method of play is given:

The cards of each suit may be considered to rank in the following order from high to low: No. 10 (scale circle), 9, 8, 7, 6, 5, 4, 3, 2, 25 and 1 (scale-ladder).

Any player may open the game by shuffling and dealing the cards one at a time, until all cards are dealt, or the last four cards or any cards left after the players 30 have an equal number may be reserved as "the widow," if so agreed. The deal passes to the left.

An object of the game is for a player to hold in his hand several of the highest and 35 the lowest "trumps" to catch tricks, scale-circles, No. 5 cards, and scale-ladders.

Bidding may begin with the player to the left of the dealer, each player naming the number of points he offers to make. A 40 player not wishing to bid may pass. Each player is allowed one bid only, and each must bid higher than the preceding bidder or pass. The highest bidder names the "trump" suit. The lowest bid allowed is "50."

45 The highest bidder—that is, the one that gets the bid—must call trumps as follows: "major flats," "major sharps," "minor flats," or "minor sharps"; if he call by colors, he forfeits his bid, and the next highest bidder 50 may take the bid, if he so desires, or the cards may be shuffled and dealt again.

The highest bidder leads first, but he does

not have to lead trumps if he calls trumps before he leads.

Each player in turn must follow the suit 55 led, if he has a card of that suit; otherwise, he may trump or discard a card of another suit. The highest card played of the suit led wins the trick, unless it is trumped when the highest trump played wins.

60 In scoring points, value may be given the various cards as agreed upon. Thus scale-circles may count 10 points, No. 5 cards 5 points, scale-ladders 5 points, and most tricks 20 points. The total number of points 65 is 100.

If the highest bidder fails to make the 70 number of points bid, he is set back the amount bid. The game may be for any number of points agreed upon.

Having thus described my invention, what I claim as new, and desire to secure by Letters Patent, is—

75 1. In a pack of playing-cards, a suit comprising a series of cards bearing designations of the musical scale and a card bearing a representation showing by its parts the correct intervals of the scale.

2. In a pack of playing-cards, a suit comprising a series of cards bearing designations of the musical scale, a card bearing a representation showing by its parts the correct intervals of the scale, and a card bearing in progressive order the designations of 80 other cards of the suit.

85 3. In a pack of playing-cards, a major-flat suit, a major-sharp suit, a minor-flat suit, and a minor-sharp suit, each suit comprising a series of cards bearing designations of the musical scale of the class to which the suit pertains.

90 4. In a pack of playing-cards, a major-flat suit, a major-sharp suit, a minor-flat suit, and a minor-sharp suit, each suit comprising a series of cards bearing designations of the musical scale of the class to which the suit pertains, a card bearing a representation showing by its parts the correct intervals of the scale, and a card bearing in progressive order the designations of 95 other cards of the suit.

100 In testimony whereof I affix my signature.

WINNIE D. DEAL.
